Application June 20, 1951, Serial No. 15,608

Term of patent 14 years

(Cl. D7—7)

To all whom it may concern:

Be it known that we, Jervis H. Sloan and Marian H. Gilkerson, respectively, a citizen of the United States, residing at St. Louis in the State of Missouri, and a citizen of the United States, residing at Chesterfield in the county of St. Louis and State of Missouri, have invented a new, original, and ornamental Design for a Shoe, of which the following is a specification, reference being had to the accompanying drawing, forming a part thereof, and in which:

We claim:

The ornamental design for a shoe, as shown and described.

JERVIS H. SLOAN.
MARIAN H. GILKERSON.
